(57) **CLAIM**

I claim the ornamental design for a recessed light, as shown
and described.

DESCRIPTION

FIG. 1 is a front view of a recessed light showing my new
design;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a front perspective view thereof; and,

FIG. 8 is a bottom perspective view thereof.

The shade lines shown in the drawings indicate the character
and contour of surfaces represented and should not be
confused with surface ornamentation.
